CLAIM

The ornamental design for a wine rack as shown and described.

DESCRIPTION

FIG. 1 is a front perspective view of a shelf for a wine rack shown isolated on its own for clarity of the disclosure.

FIG. 2 is a bottom perspective view thereof.

FIG. 3 is a left side elevation view thereof.

FIG. 4 is a right side elevation view thereof.

FIG. 5 is a front elevation view thereof.

FIG. 6 is a top plan view thereof.

FIG. 7 is a bottom plan view thereof.

FIG. 8 is a cross-sectional view of the shelf for the wine rack taken along line 8-8 shown in FIG. 3.

FIG. 9 is a cross-sectional view of the shelf for the wine rack taken along line 9-9 shown in FIG. 6.

FIG. 10 is a cross-sectional view of the shelf for the wine rack taken along line 10-10 shown in FIG. 6.

FIG. 11 is a cross-sectional view of the shelf for the wine rack taken along line 11-11 shown in FIG. 6.

FIG. 12 is a cross-sectional view of the shelf for the wine rack taken along line 12-12 shown in FIG. 6.

FIG. 13 is a frontal perspective view of a wine rack.

FIG. 14 is a frontal exploded perspective view thereof; and, FIG. 15 is a perspective view of the wine rack in use on shelving within its area of usage.

The broken lines show portions of the environment that form no part of the claimed design.
